BLOOD TRANSFER APPARATUS

Peter F. Salisbury, Los Angeles, Calif.

Application January 10, 1949, Serial No. 70,013

13 Claims. (Cl. 128—214)

1

This invention relates to blood transfer. It deals particularly with that branch of the medical art in which all or a large part of the blood supplies of two persons are interchanged.

The basic object of the invention is to provide a method and apparatus for effecting and for metering the interchange of blood between a patient and a donor in a manner to equalize the flow in each direction. Another object is to provide a blood transfer apparatus having primary means for approximately metering the flow of blood in both directions and having additional means for correcting any errors in measurement occurring in the operation of the primary metering means.

A further object of the invention is to provide an improved blood transfer mechanism including an improved intravenous catheter having means for protecting its inlet against being closed by an occluding membrane.

Another object is to provide a blood transfer apparatus having an improved means for eliminating gas bubbles from the blood being transferred.

Another object is to provide a blood transfer apparatus having improved pumping mechanism that will have a positive pumping action without injuring a significant number of the blood cells.

Another object is to provide a blood metering apparatus of a high degree of accuracy. In this connection my invention deals with a problem that has been a difficult one for medical science for many years past. Although numerous proposals for a blood metering apparatus have been made in the past, none have as yet been sufficiently accurate in their metering function to be completely satisfactory. I believe that my invention meets the strictest requirement for accuracy in metering.

Other objects will become apparent in the ensuing specifications and appended drawings in which;

Fig. 1 is a schematic view of an apparatus embodying my invention.

Fig. 2 is a detail sectional view of the improved metering unit of my invention.

Fig. 3 is a detail sectional view of the improved catheter of my invention.

Fig. 4 is a perspective view of the catheter.

Fig. 5 is a detail sectional view of the bubble trap of my invention.

Fig. 6 is a plan view partially in section of a multiple valve unit which may form a part of the apparatus of my invention.

Fig. 7 is a sectional view of the same taken on the line 7—7 of Fig. 6.

Fig. 8 is a front view partially in section of the improved pump apparatus of my invention.

Fig. 9 is a transverse sectional view of the pump apparatus taken on the line 9—9 of Fig. 8.

Fig. 10 is a detail sectional view of a portion of the pump taken on the line 10—10 of Fig. 8.

Fig. 11 is a schematic diagram of an apparatus embodying a modified form of my invention.

Referring now to the drawings in detail, I have represented schematically in Fig. 1, purely as an illustration of one possible embodiment of the invention, the

Arrangement of apparatus in general

A and B represent two human bodies between which the blood is being interchanged. Into a vein of each of these bodies is inserted a double lumen catheter C having a withdrawal channel 10 and an injection channel 11. Blood is pumped from the withdrawal channel 10 by pumps P and P¹ into metering units M and N. Each of the metering units M, N comprises a cylinder 12 and a floating piston 13 defining with the respective ends thereof chambers 14, 15, 16 and 17 respectively. From the pumps P, P¹ a series of valve controlled delivery tubes 18, 19, 20 and 21 lead through connections 22, 23, 24 and 25 to the cylinders 12 of the respective metering units 15 and N, and from the connections 22, 23, 24 and 25, a series of return lines, also valve controlled, lead back to the injection channels. These return lines are indicated at 26, 27, 28 and 29 respectively. The return lines 26 and 28 are 20 joined to the injection channel of body A by a common connection 30 and the return lines 27 and 29 are joined to the injection channel of body B by a common connection 31.

I contemplate employing plastic tubing for the 35 delivery lines 18—21 and for the return lines 26—29. In such event, there will preferably be an individual valve for each of these tubes, as described in detail hereinafter, and the valves will be of the type embodying clamping jaws for 40 constricting rubber tube sections of the lines and thereby shutting off the flow therethrough. As an example of such a valve, I have shown clamping jaws 32 for shutting off the flow through rubber tube sections 33 and 34 connecting withdrawing 45 channels 10 to the inlets of pumps P and P¹ respectively. However, for simplicity in illustrating schematically the general arrangement, I have shown (for the purpose of connecting tubes 18 and 27 to connection 23, tubes 19 and 26 to connection 22, tubes 21 and 28 to connection 24 and tubes 20 and 29 to connection 25), two way valves 35, 36, 37 and 38, each of which is in effect two valves having a common connection to connections 22, 23 etc. Each of these valves 50 is adapted to alternately connect a delivery tube to one end of a respective metering unit M, and a return tube to the other end of the metering unit, and to then connect a return tube to the said one end of the metering unit and a delivery tube to the said other end, thereby reversing the 55

direction of movement in the metering unit. The connections are such that in one half cycle of operation, while blood from a patient is being pumped into one end of one metering unit, blood from the donor is being pumped out of the other end of such metering unit and injected into the patient, while blood from the donor is being pumped into one end of the other metering unit and blood from the patient is being forced out of the other end of such other unit and injected into the donor. In the alternate half cycle of operation, the blood that was pumped into the one metering unit from the patient in the preceding half cycle, is moved on to the donor, while the blood that was pumped into the other metering unit from the donor is moved on to the patient. Thus there is a substantially continuous flow in both directions, interrupted only by short intervals in which the reversals take place. This return pumping action is effected by the movement of the piston 13 of the metering unit, moving under the pressure imparted to it by the incoming blood.

Each pump P, P¹ delivers through a connecting tube 39 into a bubble trap T, T¹, and from the traps T, T¹, the blood, with bubbles removed, passes to delivery tubes 18, 19, 20 and 21 through common connection 40 to delivery tubes 18 and 20 and through common connection 41 to delivery tubes 19 and 21.

At this point it may be noted that the above described delivery and return lines and connections collectively provide two separate pairs of flow circuits, one pair of which is operative to conduct fluid in one half cycle of operation and the other pair of which is operative in the other half cycle of operation. One such pair of circuits includes lines 19 and 27, 20 and 28 and the other includes lines 18 and 26, 21 and 29. For assistance in placing the four circuits, it may be noted that the respective circuits are shown at the respective four corners of Fig. 1.

The pistons 13 move slowly from one end to the other of their respective cylinders and then reverse their direction and move back to their starting point. The reversal of flow is controlled by valves 35 to 38, and the valves in turn are controlled by the limit movements of pistons 13. As an example of an interlinking control mechanism that can be utilized for controlling the flow in the desired manner, I have shown an electrical system which includes micro-switches 42, 43, 44 and 45, mounted in the respective ends of the cylinders 12, in position to be engaged by the pistons 13 at the limits of their respective strokes. The micro-switches operate mechanism which functions to synchronize the movements of the two pistons so that they will always start their new strokes simultaneously. Thus the same number of strokes is made by each piston. Since the aggregate capacity of chambers 14 and 15 is equal to the aggregate capacity of chambers 16 and 17, the same average rate of flow of blood will be maintained in both of the flow circuits that are in operation. Specifically, each micro-switch, when engaged by a piston 13, arrests the circulation of fluid in its particular circuit until the other piston has reached the end of its travel. It is, of course, contemplated that ordinarily the two pistons will end their strokes simultaneously, but should one piston for any cause travel ahead of the other piston in the respective strokes, the micro-switch of the leading piston will function to delay it so that the two pistons can start their next strokes simultaneously. The micro-switches

have the further function of effecting the reversal of the valves 35, 36, 37 and 38 when both pistons have completed their respective strokes, and thereby causing the arrested piston to resume its movement.

Purely as an example of a control system that may be utilized to carry out these operations, I have shown an arrangement in which each micro-switch 42, 43, 44, 45 forms parts of a control circuit including a source of electric power E, a power lead conductor 46, a conductor 47, a relay energizing coil 52, and a ground or return connection 53. The micro-switches, when contacted by their respective pistons, are closed and thereby function to actuate corresponding double relays 48, 49, 50, 51, each including an energizing coil 52.

The valves are shifted by an electrically operated mechanism such as, for example, a servomotor 59 including two energizing coils 58, 58¹. The coils 58, 58¹ are each controlled by conjoint action of paired relays, both of which must be actuated before the servomotor is energized. Servomotor coil 58 is controlled by paired relays 48 and 50. Servomotor coil 58¹ is controlled by paired relays 49 and 51. Each of these paired relays servomotor control circuits includes contact heads 54 of the paired relays, sets of contacts 55 and 56 bridged by the respective heads 54, conductors 57 leading from contacts 56 to coils 58, 58¹, a connection between one contact 55 and power lead 46, and a connection between the other contact 55 and ground or a return connection, indicated at 60. Each pair of relays is thus in series with an energizing coil 58 or 58¹ and both relays must be closed before the servomotor 59 is actuated to shift the valve. Accordingly, the valve will not be shifted until both pistons have reached the ends of their strokes.

40 A second contact head 61 of a respective relay, electrically insulated from the head 54, is adapted to engage contacts 62 and 63, the former connected to the power lead 46 and the latter connected to a bridging conductor 64 which connects the contacts 63 of paired sets of relays together in parallel with the energizing coil 66 through a conductor 67 having a limit switch 68 in series therein. Each limit switch 68 is actuated by the servomotor 59 as it shifts the valves. The limit switches 68 may be spring biased to closed positions and opened by being contacted by the armature of servomotor 59, as indicated. Thus each limit switch will normally maintain a connection between its associated conductors 67 to set up a circuit for energizing a valve solenoid 65 as soon as the circuit has been closed between the corresponding pairs of relays 48, 50 or 49, 51.

Before describing in detail the operation of the apparatus, I will describe a number of the novel parts of the apparatus, beginning with the

Metering unit

The metering unit (Fig. 2), M, N, are chiefly characterized by the fact that the piston 13 floats in the cylinder 12 and responds solely to the pressure of fluids thereagainst. It is of sufficient axial dimension to maintain a true transverse position within the cylinder 12, avoiding canting and binding, and is fitted with the cylinder 12 with sufficient clearance to move freely back and forth, while permitting only a minimum amount of leakage of fluid between its periphery and the wall of the cylinder.

The problem of leakage has been considered, 75 and the invention provides for an equal leakage

in both directions, so that the leakage in one direction will balance the leakage in the other and thereby avoid any inaccuracy in the metering function of the apparatus.

The cylinder 12 and piston 13 are both preferably constructed of plastic material, and the cylinder 12 may be transparent in order that the action within the metering unit may be observed by the operator. The switches 42, etc., are of the type known in the trade as "microswitches" and each includes a plunger 70 to be engaged by a piston 13. The opening in the end wall of the cylinder, through which the plunger 70 passes, may be sealed in any suitable manner, as, for example, by means of a flexible diaphragm 71 covering the plunger, and transmitting movement to the plunger. Instead of a floating piston, the metering unit may utilize a piston having a piston rod, or may utilize a flexible diaphragm to separate its chambers.

Catheter

Each catheter C (Fig. 3) is of double-tube construction comprising the withdrawal channel 10 and the injecting channel 11, the withdrawal channel 10 having a receiving mouth which is formed in a bevelled end of the withdrawal channel 10, said bevelled end forming an overhanging lip 73. The injection channel 11 is continued beyond the lip 73 to form a nozzle 14. The overhanging characteristic of the lip 73 functions to prevent the wall of a vein 75 or other occluding membrane from collapsing against the mouth of withdrawal channel 10 so as to close the same. In use, the catheter is, in accordance with conventional practice, inserted into a vein as indicated in Fig. 3, the projecting nozzle 14 extending downstream from the receiving mouth so as to minimize commingling of the blood being withdrawn from the vein and that being returned to the vein. In this respect, the invention is a definite improvement over existing catheters which are all subject to the objection that the mouth of the withdrawal tube is frequently closed by the wall of a vein or other surrounding membrane.

Bubble trap

The improved bubble trap of my apparatus comprises a reservoir 76 which is positioned vertically when in use, the pump outlet line 39 being connected to an upwardly inclined inlet 77 communicating with the reservoir 76 intermediate its upper and lower ends, and the common connection 40 or 41 being connected to an outlet 78 which communicates with the bottom of the reservoir 76.

Communicating with the top of the reservoir 76 is a manometer 79 having an upwardly extending terminal leg 80 to the upper end of which is attached a mercury trap. The mercury trap comprises a shell 81 having an inlet 82 forming a continuation of the upper end of leg 80 of the manometer and having an outlet 83. The inlet 82 and outlet 83 extend into the trap in overlapping relation as shown in Fig. 5, so as to make it practically impossible for any mercury to be blown from the inlet 82 through the outlet 83 under any sudden increase of pressure in the bubble trap. The function of the manometer, of course, is to indicate at all times the pressure of gas which is trapped in the space 84 above the pool of blood 85 in the bubble trap. At intervals, the collected gas may be allowed to escape from the chamber 84 through a bleed tube 86 75 crank 114 through a pair of connecting rods 116

communicating with and extending upwardly from the top of the reservoir 76. Normally, bleed tube 86 is closed by a clamp valve 87 constricting closing a flexible tube nipple 88 on the upper end of the bleed tube 86.

In my apparatus, the bubble trap has an improved operation resulting from the pulsating nature of the pumping action. It appears that because of the fluctuation in pressure resulting from this pulsating action, there is considerably more of a tendency for the collected gas to be reabsorbed in the blood within the trap than is the case where a more steady pressure is utilized for forcing the fluid through the system.

Valve unit

Figs. 6 and 7 illustrate a preferred arrangement of valve mechanism, and operating means therefor. Fig. 11 discloses how this valve mechanism 20 may be arranged in a cross transfusion system embodying the invention. There are eight valves, each comprising a section of flexible tubing of rubber or the like, and all actuated by a common actuator plunger 89. The plunger 89 is 25 slidably mounted in a casing 90 which has a series of bores 91 in which the valve tubes are mounted. The valve tubes are numbered 35a, 35b, 36a, 36b, 37a, 37b, and 38a, 38b, corresponding to the pairs of ports controlled by the two 30 way positions of the valves 35, 36, 37 and 38 of Fig. 1. The plunger 89 has a series of operating fingers 92 positioned to engage and collapse the tubes 35a, 35b, etc. In one operative position of plunger 89, valve tubes 35a, 36a, 37b and 38b will 35 be collapsed, and in the other operative position of the plunger 89, the valve tubes 35b, 36b, 37a and 38a will be collapsed (see Fig. 11).

The plunger 89 is slideable longitudinally in a 40 slideway 94 in the casing 90 (which may be in two halves, secured together by bolts 95) and the operating fingers 92 may be accommodated in recesses 96 communicating with the slideway 94.

The valve unit is actuated by an electric servomotor which may take the form of a small electric motor 97 operating, through a reduction gear 98, an eccentric 99 connected by a pitman 100 to the plunger 89. In 180 degrees of rotation of eccentric 99, the valve plunger will be shifted to one limit of movement while in the balance of one rotation of the eccentric 99, the valve plunger will be shifted back to its starting position, i. e., its alternative operating position.

Pumping unit

55 Each of the pumps P and P¹ comprises a base 104 into which is threaded a pair of adjustable supporting posts 105. The upper ends of the posts 105 have rotatable connections with a cradle 106, for supporting the same. A flexible tube 60 107 is supported in a channel 108 in the cradle 106. An upright 109, rising from the base 104, has a pair of ears 110 projecting forwardly over the base. Journalled in the ears 110 is an operating shaft 111 which has a pair of cams 112, 112, spaced apart and a pair of eccentric bearings 113 located between the cams 112. The cams 112 may be formed as integral parts of the shaft 111, and are arranged at 180 degrees angularity with reference to each other about the axis of the shaft. The eccentric bearings 113 are mounted on a reduced central shaft portion 114 which is disposed eccentrically with respect to the axis of the shaft 111 so as to constitute a crank. A piston or pressure pad 115 is operated by the 65 70 75 80 85 90 95 100 105 110 115 116

secured to and rising from the piston 115, and pivoted at 117 at their upper ends to bearings 113.

Valve plungers 118, 118¹, arranged one at either end of the piston 115, are operated by the cams 112 in alternating sequence. The cams 112 are arranged symmetrically on opposite sides of the axis of crank 114, so that, when the shaft 111 is rotating in one direction, downward movement of piston 115 will be preceded by downward movement of one of the valve plungers, and when the shaft is rotating in the opposite direction, downward movement of the piston 115 will be preceded by downward movement of the other valve plunger. Thus the direction of flow may, if desired, be reversed by reversing the direction of rotation.

The lower extremities of valve plungers 118, 118¹ and piston 115 are embraced between the side walls of channel 108 and the upper ends of the plungers 118 and the connecting rods 116 are provided with longitudinal slots 119 which receive a guide rod 120. Thus the valve plungers and connecting rods are guided for vertical reciprocating movement. The ends of rod 120 are mounted in ears 110.

In the operation of the pump, rotation of shaft 111 will, through cams 112 and 113, depress the valve plungers 118, 118¹ and piston 115 in a sequence depending upon the direction of rotation of shaft 111. For example, if the shaft, as viewed in Fig. 9, is rotating in a clockwise direction, it will depress first the valve plunger 118, closing off the tube 107 at the left end of piston 115 as viewed in Fig. 8, will then gradually press the piston 115 downwardly against the tube 107, collapsing the portion thereof between valve plungers 118 and 118¹ and forcing the contents of said tube portion along the tube in the direction indicated by arrow 119. As the piston 115 nears the bottom of its stroke, valve plunger 118¹ will move downwardly and will close the tube on the right end of piston 115 as the latter commences to travel upwardly. Valve plunger 118 will move upwardly slightly ahead of the upward movement of piston 115, and the collapsed portion of tube 107 will regain its normal cylindrical shape and will communicate with the adjacent area of the tube to the left of valve plunger 118, drawing a fresh quantity of blood into its interior, which quantity is expelled upon the next downward stroke of the piston 115, in the direction of flow indicated by arrow 419.

My improved pump has the advantage of avoiding destruction of any significant number of blood corpuscles. Ordinarily, the piston 115 will be operated so as to collapse the tube 107 to a point just short of actual contact between the walls of the tube, in order to avoid crushing the blood corpuscles between the walls of the tube. A slight amount of such crushing will occur where the valves engage the tube but is sufficiently negligible to be unobjectionable.

The pumping rate may be varied by adjusting the height of cradle 106 (through posts 105) and thereby varying the effective stroke of piston 115.

Modified arrangement of apparatus

In the preferred arrangement of apparatus embodying my invention, shown schematically in Fig. 11, the valve unit of Figs. 6 and 7 is illustrated with the valve tubes 35a, 35b, etc., shown in a somewhat different arrangement from that of Figs. 6 and 7, for the sake of clarity in the schematic lay-out of the complete apparatus. The fluid circulating system is substantially the

same as that shown in Fig. 1, and similar reference characters are used to designate the same. Microswitches 68 and 68¹ are actuated by the respective ends of valve plunger 89 (see Fig. 6). The metering units M and N, and microswitches 42, 43, 44 and 45 associated therewith, are the same as in Fig. 1. Relays 48¹, 49¹, 50¹ and 51¹ correspond to relays 48, 49, 50 and 51 of Fig. 1, but are each provided with three sets of contacts instead of two. For each relay, the three sets of contacts are identified with the reference letters a, b and c respectively. Contacts a function to set up holding circuits for the respective relay operating coils 52; contacts b control the operation of servo motor 97; and contacts c control the operating of valve solenoids 66, 66¹ of clamp valves 32, 32¹.

A source of power E is connected by a main power lead 46 through a series of branch power leads 46a, 46b, 46c and 46d to one side of each microswitch 42, 43, 44 and 45 respectively, and through branch power leads 46e and 46f to one contact of each pair of contacts a. From the other side of each microswitch 42, 43, 44 and 45 respectively, conductors 47a, 47b, 47c and 47d are connected to one side of each of the respective relay coils 52 and are also connected to the other contacts of pairs of contacts a. A conductor 121 connects the other sides of the energizing coils 52 of relays 48¹ and 50¹ to ground G through microswitch 68 and conductor 122. Similarly, a conductor 121¹ connects the other sides of energizing coils 52 of relays 49¹ and 51¹ to ground G through microswitch 68¹ and conductor 122¹. Motor 97 is arranged to be placed in series with two sets of contacts b. In one phase of operation, motor 97 is energized by the closing of relays 48¹ and 50¹, being connected to a contact b of one of these relays by conductors 123 and 123¹, and being connected to a contact b of the other of these relays by conductors 124 and 124¹. In another stage of operation, the motor 97 is placed in series with the contacts b of relays 49¹ and 51¹, being connected to one of such contacts by conductors 123 and 123¹ and being connected to the other of these contacts by conductors 124 and 124¹. The co-acting contacts b of relays 48¹ and 51¹ are connected to branch power leads 46f, and the co-acting contacts b of relays 49¹ and 50¹ are connected to ground G by conductors 125, 122 and 125¹, 122¹. It will now be apparent that when a pair of relays 48¹ and 50¹ (or 49¹ and 51¹) are both energized, one of these relays will connect one side of servo motor 97 to power source E through conductors 123, etc., whereas the other of the pair of relays will connect the other side of the servomotor 96 to ground through conductors 124, etc.

An auxiliary source of electric power E¹ is connected to one contact of each of the four pairs of contacts c by conductors 126, 126¹, 126². The co-acting contacts c of relays 48¹ and 51¹ are connected by a conductor 127 to one side of valve operating solenoid 66, and the co-acting contact c of relays 49¹ and 50¹ are connected by a conductor 127¹ to one side of the other valve operating solenoid 66¹. The other sides of the respective solenoids 66 and 66¹ are connected to ground, indicated at G¹, by conductors 128 and 128¹ respectively.

Relays 48¹, 49¹, 50¹ and 51¹ are self opening, i. e., spring biased toward open positions.

Method and operation of apparatus (Fig. 1)

My invention provides an improved method of exchanging blood between a patient and a donor.

in which the blood of the donor is positively pumped into the body of the patient while an equal quantity of blood from the patient is positively pumped into the body of the donor. Such an exchange of blood can be utilized to advantage in the treatment of disease in which the blood of a patient is non-infectious but has an excess of waste products such as urea or bile, or a deficiency of needed elements such as blood sugar, proteins or hormones.

The invention also embodies an improved method of measuring the transferred volumes of blood by (a) counting (as by means of the counter 130 shown in Fig. 1) the number of times the valve bank reverses the flow and (b) multiplying by the volume of a metering chamber at its fully expanded condition.

Extreme accuracy of metering action is obtained by balancing leakage in one direction against the equal leakage in the other direction. Any mixing of the bloods of donor and patient that may result from such leakage is unobjectionable, since the ultimate effect of the apparatus is to produce a mixture of the donor's blood with the patient's blood.

In treating a patient, the blood is first treated with an anti-coagulant in accordance with known procedure and the apparatus is then attached by inserting catheters C into veins 15 of the donor A and patient B respectively. The apparatus is started simply by starting the operation of pumps P and P¹.

In a first half cycle of operation, which may be, for example, that illustrated in Fig. 1, the blood withdrawn from donor A will be pumped by pump P through bubble trap T into common delivery channel 40, from which the two branch delivery channels 18 and 20 branch off to the respective metering units M and N. Simultaneously, blood withdrawn from the veins of the patient B will be pumped by pump P¹ through bubble trap T¹ into common delivery channel 41 leading to branch delivery channels 19 and 21. In this first half cycle of operation, delivery channels 18 and 21 will be blocked at the closed ports of valves 36 and 38 respectively, and the fluid flow will be directed, as indicated by arrows 101, to the open ports of valves 35 and 37, and thence to metering unit connections 22 and 25 of the respective metering units M and N. Thence the fluid will enter chambers 14 and 16 of the respective metering units and will move pistons 13 in the direction indicated by arrows 102, forcing the fluid out of chambers 15 and 17, through connections 23 and 24, and through branch return lines 27 and 28, as indicated by arrows 103, to common return lines 31 and 30, and thence to catheter channels 11 into the veins of patient B and donor A respectively. When the pistons 13 reach the ends of their strokes, they will engage and close limit switches 43 and 45, establishing circuits through conductors 46 and 47 and relay energizing coils 52 to close relays 49 and 51. The closing of these relays establishes a circuit which includes power leads 46, relay contacts 54, 55 and 56, conductors 57, and ground 60, to energize servomotor coil 58¹ and shift valves 35, 36, 37 and 38 to their alternate positions.

Should one of the pistons 13 reach the end of its stroke ahead of the other, the servomotor circuit would remain open because of the coil 58¹ being in series with both relays 49 and 51. During the interim between the completion of the stroke of the one piston and the completion of the stroke of the other piston, a circuit for effect-

ing the interruption of flow to the metering unit in which the piston has completed its stroke, will be established. For example, assuming that the piston of metering unit M has completed its stroke and has closed microswitch 43 while microswitch 45 remains open, a circuit will be established from power lead 46 through contacts 61, 62 and 63 of relay 49, conductors 64 and 67 and limit switch 68 to coil 66 of valve operator 65, closing constrictor valve 32 against flexible tube 34 to shut off the flow of blood to pump P¹ and thereby arrest the flow circuit through metering unit M while flow through metering unit N continues. At the end of the stroke of piston N, limit switch 45 will be closed to energize relay 51, completing the circuit to servomotor coil 58¹, as described above, causing the servomotor to shift the valves to the alternate position, and opening limit switch 68 to re-establish the flow passage between patient B and pump P¹.

The reversal of the valves establishes a second half cycle of operation, in which blood from donor A is pumped through alternate branch channel 18 and connection 23 to chamber 15 of metering unit M, while patient's blood from chamber 14 is moved through connection 22 to return conduit 26 and thence to common return 30 from which it is injected into donor A. Simultaneously, patient's blood will be delivered through branch delivery conduit 21, valve 38 and connection 24 into chamber 17 of metering unit N, while donor's blood from chamber 16 will be delivered through connection 25, valve 37, branch return conduit 29 and common return 31 into the patient's veins. At the end of the strokes of the two pistons in this half cycle of operation, microswitches 42 and 44 will be closed to establish the circuit through servomotor coil 58 which shifts the servomotor and valves back to the positions shown in Fig. 1. Should either piston reach the end of its stroke ahead of the other, the flow to the corresponding metering unit will be shut off by the action of constrictor valve 32 on connecting tube 33 by a circuit established through limit switch 68 in a manner similar to that described above, and the flow circuit from donor A to pump P, thus temporarily arrested, will be re-established by the opening of limit switch 68 when the servomotor has been shifted back to the position shown in Fig. 1.

Operation of apparatus of Fig. 11

The operation of the apparatus of Fig. 11 is similar to that of the apparatus of Fig. 1, the main difference being the somewhat different arrangement of electrical connections that are set up. Assuming each piston 13 to be in the middle of its stroke, moving in the direction indicated by arrow 129, the flow through the lines 18, 26, 21 and 29 will be as indicated by the arrows adjacent to those lines, and the lines 19, 27, 20 and 28 will be shut off by the closing of valves 35b, 36b, 37a and 38a respectively. Microswitches 68 and 68¹ at the respective ends of valve actuator 89 will be closed and open respectively. When the pistons 13 reach the ends of their respective strokes, they will close microswitches 42 and 44. As each of these switches is closed, it will establish a circuit from source of current E through conductor 48 and branch conductor 48a (or 48c), conductor 47a (or 47c), to an energizing coil 52 of a respective relay 48¹ (or 50¹) grounded through conductor 121 (or 121¹), microswitch 68 (or 68¹) and conductor 122 (or 122¹). As each of these relays is energized, it will establish (a)

a holding circuit through contacts *a* from power lead 46¹ through its respective energizing coil 52 to ground through conductors 121 (or 121¹), etc.; (b) a circuit to one side of servomotor 97 through contacts *b* from power lead 46¹ through conductors 123¹, 123 (or 123'', 123); and (c) a circuit to a corresponding valve operating solenoid 66 (or 66¹) through contact *c* from power lead 126, etc., to conductor 127 (or 127¹) to ground connection 128 (or 128¹), closing the respective valve 32 (or 32¹).

When both relays 48¹ and 50¹ have been energized, a circuit through servomotor 97 will be completed, from power lead 46¹ through contacts *b* of relay 48¹, conductors 123¹, 123 to the servomotor, thence from the other side of the servomotor to conductors 124, 124¹, contacts *b* of relay 50¹, and thence to ground through conductors 125. It will now be apparent that this servomotor energizing circuit goes through both of the pair of relays 48¹ and 50¹, in series, and that the servomotor is not energized until both relays have been closed. The servomotor will operate, transmitting movement from eccentric 99 to valve plunger 89 until the latter has shifted to its alternate position, opening valves 35b, 36b, 37a and 38a, closing valves 35a, 36a, 37b and 38b, and opening microswitch 68, thus breaking the ground connection to the energizing coils of relays 50¹ and 48¹, and causing both of these relays to resume their open position. All contacts *a*, *b* and *c* will be thereby opened, resulting in: (a) releasing the holding circuits; (b) de-energizing the servomotor 97 and stopping the movement of valve plunger 89 at its alternate position; and (c) de-energizing both valve solenoids 66 and 66¹, thus re-opening the valves 32, 32¹ to re-establish flow in both flow circuits. In an early stage of the movement of valve plunger 89, the microswitch at 68¹ is released and consequently returns to its closed position, setting up the ground connections to ground G from energizing coils 52 of relays 49¹ and 51¹. During the ensuing half cycle of operation, pistons 13 will move in the direction opposite to the directions indicated by arrows 129, metering the flow of blood through the alternate circuits including flow lines 19, 27, 20 and 28, now open. At the end of this half cycle of operation, limit switches 43 and 45 will be closed, energizing relays 49¹ and 51¹, again closing valves 32 and 32¹ and operating servomotor 97 in the manner described above, but through the alternate circuits including (b) a servomotor circuit from power lead 46¹ through contact *b* of relay 51¹, conductors 123'', 123, 124 and 124'', contact *b* of relay 49¹, and conductor 125¹ to ground through limit switch 68¹; (c) valve operating circuit from power lead 126¹ through contacts *c* of relay 51¹, and conductors 127 and 128; and valve operating circuit to solenoid 66¹ from power lead 126¹ through contact *c* of relay 49¹, and conductors 127¹ and 128¹.

I claim:

1. In a blood transfer apparatus, in combination with a pair of catheter means for insertion into blood channels of respective bodies, each including an injection device and a withdrawal device, a pair of metering units each including means defining opposed fluid chambers, and a movable element separating said chambers and movable in response to fluid pressure in one of the chambers; a pair of pumps; and a plurality of conduits and valves interconnecting said pumps, catheter means and metering units to provide two sets of flow circuits one of which is opera-

tive in one half cycle of operation of said apparatus to direct blood from the respective bodies into one end of each of the respective metering units while directing flow from the other ends of the respective metering units into the respective bodies, and the other of which is operative in a second half cycle of operation to direct flow from the respective bodies into the said other ends of the respective metering units while directing flow from the said one ends of the respective metering units into the bodies.

2. Apparatus as defined in claim 1, including means automatically operable at the ends of the strokes of the respective movable elements of said metering units to reverse the positions of said valves.

3. Apparatus as defined in claim 1, including a bubble trap interposed between the discharge side of each pump and the flow circuits connected thereto.

4. Apparatus as defined in claim 1, wherein said metering units each comprise a cylinder and a floating piston therein adapted in response to the pressure of fluids pumped into one chamber thereof to expel the fluid from the other chamber thereof.

5. Apparatus as defined in claim 1, wherein said metering units each comprise a cylinder and a floating piston therein adapted in response to the pressure of fluids pumped into one chamber thereof to expel the fluid from the other chamber thereof, each metering unit including limit switches at its respective ends, engageable by the piston at the end limits of its stroke, and electrical means controlled by said limit switches for shifting said valves.

6. In a blood transfer apparatus, in combination with catheter means for insertion into blood channels of respective bodies, including a withdrawal device and an injection device; a pair of metering units, each including means defining opposed fluid chambers, said means including a movable element separating said chambers and movable in response to fluid pressure entering one of the chambers to drive fluid out of the other chamber; a pair of pumping units, each having an inlet communicating with a respective withdrawal device, and each having an outlet; a pair of delivery conduits branching from each of said outlets; a plurality of return conduits arranged in pairs, a common return connection between each pair of return conduits and a respective one of said injection devices; connections to the respective ends of each of said metering units, a plurality of valves operable in a first half cycle of operation to establish communication between a connection at one end of each respective metering unit and one set of said delivery conduits while simultaneously establishing communication between the connections at the other ends of said metering units and one set of said return conduits and, in a second half cycle of operation, to establish connections between said one ends of the metering units and the other set of said return conduits while simultaneously establishing connections between said other ends of the metering units and the other set of delivery conduits.

7. In apparatus as defined in claim 6, electrically operated means including switches at the respective ends of said metering units for automatically effecting the shifting of each of said valves from its one position to its alternative position at the end of the stroke of a movable element.

13

8. Apparatus as defined in claim 6, wherein said conduits are so arranged that in one half cycle of operation, one delivery conduit and one return conduit will connect the respective chambers of one metering unit to one of said bodies while another delivery and return conduit will connect the respective chambers of the other metering unit to the other body, while in an alternative half cycle of operation, alternative delivery and return conduits will connect said other and said one chamber of each metering unit to said other and said one body respectively, whereby in the first half cycle of operation blood from the one body is injected into the one chamber of one metering unit and blood from the other body is ejected from the other chamber of said one metering unit into said one body, while blood from the other body is being injected into the one chamber of the other metering unit and blood from the one body is ejected from the other chamber of said other metering unit and delivered to said other body; whereas in the other half cycle of operation, blood from the one body will be delivered into the said other chamber of said other metering unit while blood from the other body is being delivered from the one chamber of said other metering unit to said one body, and blood from the other body will be delivered to the other chamber of said one metering unit while blood from said one body is being delivered from said one chamber of said one metering unit to said other body.

9. In a blood transfer apparatus, a pair of metering units each including a movable element and means defining on the respective sides of said movable element a pair of chambers, flow connections to the respective chambers at the respective ends of each unit, a pair of conduits branching from each of said flow connections, and valves controlling each of said conduits, said valves comprising flexible tubes arranged in opposed banks and a reciprocable pressure member movable from a position simultaneously engaging one bank of tubes and closing the same to a position simultaneously engaging and closing the other bank of tubes.

10. In a blood transfer apparatus, in combination with catheter devices for insertion into blood vessels of respective bodies, including a pair of withdrawal devices and a pair of injection devices: a pair of metering units each including means defining opposed fluid chambers, said means including a movable element in each unit, separating the chambers thereof, said elements being movable to increase the volumes of one pair of chambers while decreasing the volumes of the other pair of chambers; said means further including a fluid connection for each chamber; a system of flow conduits including a pair of conduits for each of said fluid connections, leading respectively to an injection device for one body and a withdrawal device for the other body, and valve means arranged to render one series of said conduits, consisting in one conduit of each pair, collectively operative in one half cycle of operation, to conduct flows from the withdrawal devices to one of said pairs of chambers and from the other pair of chambers to the injection devices, and to render the other conduits of the respective pairs operative, in the other half cycle of operation, to conduct flows from the withdrawal devices to said other pair of chambers and from said one pair of chambers to the respective injection devices.

11. In a blood transfer apparatus, in combina-

14

tion with catheter devices for insertion into blood vessels of respective bodies, including a pair of injection devices and a pair of withdrawal devices: means defining two pairs of metering chambers and a fluid connection for each chamber for conducting flows alternately into and out of the respective chamber; a system of flow conduits including a pair of conduits for each of said fluid connections, leading respectively to an injection device for one body and a withdrawal device for the other body; and valve means arranged to render one series of said conduits, consisting in one conduit of each pair, collectively operative in one half cycle of operation, to conduct flows from the withdrawal devices to one of said pairs of chambers and from the other pair of chambers to the injection devices, and to render the other conduits of the respective pairs operative, in the other half cycle of operation, to conduct flows from the withdrawal devices to said other pair of chambers and from said one pair of chambers to the respective injection devices.

12. In a blood transfer apparatus, in combination with catheter devices for insertion into blood vessels of respective bodies, including a pair of injection devices and a pair of withdrawal devices: means defining two pairs of metering chambers and a fluid connection for each chamber; means for inducing flows alternately into and out of the respective chambers; a system of flow conduits including a pair of conduits for each of said fluid connections, leading respectively to an injection device for one body and a withdrawal device for the other body; and valve means arranged to render one series of said conduits, consisting in one conduit of each pair, collectively operative in one half cycle of operation, to conduct flows from the withdrawal devices to one of said pairs of chambers and from the other pair of chambers to the injection devices, and to render the other conduits of the respective pairs operative, in the other half cycle of operation, to conduct flows from the withdrawal devices to said other pair of chambers and from said one pair of chambers to the respective injection devices.

13. In a blood transfer apparatus, in combination with a pair of catheter devices for insertion into blood vessels of respective bodies, said devices including a pair of injection devices and a pair of withdrawal devices; means defining a plurality of metering chambers and a fluid connection for each chamber to function alternately as inlet and outlet; means for inducing flows alternately into and out of the respective chambers; a system of flow conduits including a pair of conduits for each of said fluid connections, leading respectively to an injection device for one body and a withdrawal device for the other body; and valve means controlling the flows through said conduit system, including a valve for each conduit, said valve means comprising a series of flexible tubes each constituting a portion of a respective conduit, said flexible tubes being arranged in opposed banks, and a reciprocable pressure member movable from a position simultaneously engaging one bank of tubes and closing the same, to a position simultaneously engaging and closing the other bank.

PETER F. SALISBURY.
